UNITED STATES PATENT OFFICE.

THEODORE H. KRUSE, OF ARVADA, COLORADO.

RAILROAD-TIE.

1,370,129.

Specification of Letters Patent.

Patented Mar. 1, 1921.

Application filed June 17, 1920. Serial No. 389,660.

To all whom it may concern:

Be it known that I, THEODORE H. KRUSE, a citizen of the United States, residing at Arvada, in the county of Jefferson and State 5 of Colorado, have invented a new and useful Railroad-Tie, of which the following is a specification.

It is the object of this invention to provide a railroad tie to which a rail may be 10 connected readily, novel means being provided for holding the rail on the tie, and the tie being so constructed that it will co-operate with the means whereby the rail is held.

15 It is within the province of the disclosure to improve generally and to enhance the utility of devices of that type to which the invention appertains.

With the above and other objects in view, 20 which will appear as the description proceeds, the invention resides in the combination and arrangement of parts and in the details of construction hereinafter described and claimed, it being understood that, with- 25 in the scope of what is claimed, changes in the precise embodiment of the invention shown can be made without departing from the spirit of the invention.

In the accompanying drawings:—

30 Figure 1 shows in side elevation, a tie constructed in accordance with the invention, one of the concrete end blocks being omitted; Fig. 2 is a cross section on the line 2—2 of Fig. 1; Fig. 3 is a cross section on the line 3—3 of Fig. 1; Fig. 4 is a fragmental longitudinal section taken in a vertical plane on the line 4—4 of Fig. 2; and Fig. 5 is a horizontal section taken on the line 5—5 of Fig. 1.

40 The tie includes a pair of end members 1 preferably in the form of metal plates, the end members having depending hook-shaped tongues 2 and upstanding hook-shaped tongues 3 alternating with the 45 tongues 2. In each member 1, adjacent to the outer end thereof, an opening 4 is formed, an opening 5 being fashioned in the member 1 adjacent to the inner end thereof. The constituent material of the 50 member 1, outwardly of the opening 4 and outwardly of the opening 5 is struck upwardly to form inverted troughs 6 and 7. A reinforcement 8, preferably in the form of a metal strip, extends along the upper

surface of the member 1. One end 9 of the 55 reinforcement 8 passes through the opening 4 and is engaged in the trough 6. The other end 10 of the reinforcement 8 is extended through the opening 5 and is received in the trough 7. The parts thus far described may be alluded to broadly as anchors.

The device includes a connector 11 in the form of a tube. The parts 7 and 10 pass into the connector 11 and are secured thereto in any suitable way, for instance by cotter pins 12 having their ends clenched as indicated at 14 on the lower surface of the connector 11. The anchors above alluded to are embedded in blocks 15 of concrete or 65 the like, the extremities of the parts 7 and 10 projecting beyond the inner end of the block 15. The connector 11 abuts at its ends 70 against the inner ends of the blocks 15.

On the block 15 is placed a base plate 16 75 provided in its ends with slots 17. A rail 19 rests on each base plate 16. Braces 20 are mounted on the block 15 and co-operates with the rail 19, the braces being shaped to overlap the base flange of the rail 19, as 80 shown in Fig. 4. The braces 20 have recesses at their inner ends, as indicated at 23, so as to receive the base plate 16. The material freed in the formation of the slots 17 in the base plate 16 is fashioned into 85 tongues 18 which extend upwardly through openings 21 in the bottom portions of the braces 20, the tongues being clenched on those portions of the braces 20 which lie above the base flange of the rail 19. Se- 90 curing members 22, which may be screws, pass downwardly through the bottom portions of the braces 20, through the base plates 16 and into the reinforcements 8 and the end members 1. Although the screws 95 22 constitute a part of the rail fastening means, the said screws exercise a function in the tie construction *per se*, since they serve to connect the reinforcements 8 and the end members 1, these last specified elements forming a part of the tie. A legitimate combination, thus, is made out between the rail fastening means and the railroad 100 tie construction.

The tie hereinbefore described may be ad- 105 justed for gage, by substituting the connector 11 of a given length for another connector of a different length. The rails 19 will

be adequately supported on the blocks 15, and the anchors will remain firmly engaged in the blocks.

Having thus described the invention, what is claimed is:—

1. In a device of the class described, spaced blocks; anchors embedded in the blocks, the ends of the anchors projecting beyond the inner end of the blocks; a tubular connector abutting against the inner ends of the blocks to space the blocks, and receiving the ends of the anchors; securing elements uniting the ends of the anchors with the ends of the connector; and a rail fastening means including a part extended downwardly into each block into engagement with the corresponding anchor.
2. In a device of the class described, base blocks; plates embedded in the blocks, the plates being provided along their edges with alternating upstanding and depending tongues, the tongues being hook-shaped to extend above the plate and to extend beneath the plate, the plates including end portions projecting beyond the inner ends of the blocks; means for connecting the ends of the plates detachably; and a rail fastening means comprising a part extended downwardly through the block into engagement with the plate.
3. In a device of the class described, a

plate having openings; a reinforcement superposed on the plate and having its end portions extended through the openings; a block wherein the plate and the reinforcement are embedded; a rail brace on the blocks; and a securing member connected with the rail brace and extended downwardly into the block, into engagement with the reinforcement and the plate.

4. In a device of the class described, a plate; a reinforcement superposed on the plate, the plate having openings into which the ends of the reinforcements project; a body wherein the plate and the reinforcement are embedded; a base plate on the block; a rail on the base plate; a brace cooperating with the rail, the base plate having a tongue extended upwardly through the brace; and a securing member passing through the brace, the base plate and a portion of the block, the securing member engaging the first specified plate and the reinforcement to connect the same.

In testimony that I claim the foregoing as my own I have hereto affixed my signature in the presence of two witnesses.

THEODORE H. KRUSE.
